F. WALDORF

WRITING INSTRUMENT

Filed Feb. 13, 1922

Inventor.
Frederick Walderff.
By J. C. H. M. Stringer,
Atty.

UNITED STATES PATENT OFFICE.

FREDERICK WALDORF, OF ERIE, PENNSYLVANIA.

WRITING INSTRUMENT.

Application filed February 13, 1922. Serial No. 536,217.

To all whom it may concern:

Be it known that I, FREDERICK WALDORF, a citizen of the United States, residing at Erie, in the county of Erie and State of Pennsylvania, have invented certain new and useful Improvements in Writing Instruments; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to writing instruments and has for its object the combination of an adjustable lead pencil mechanism and a fountain-pen mechanism in a single structure.

Another object of this invention is to provide mechanism which can be actuated by the adjustable pencil mechanism to fill the ink-chamber.

In constructing a writing instrument according to this invention, I provide a hollow handle adapted to receive and retain the nib-holder of a fountain pen, of ordinary construction, which handle may be filled with fluid when desired. In the opposite end of said hollow handle the mechanism of an adjustable lead-pencil is secured, a necessary portion of which extends into said hollow handle, where it is provided with means whereby fluid can be drawn into said hollow handle, the portion of the pencil mechanism extending into said hollow handle having the double purpose of operating the pencil adjusting mechanism when longer or shorter lead is desired, and as a piston rod, when filling the hollow handle.

These and other features of this invention will appear hereinafter in the specification and claims and are illustrated in the accompanying drawings in which:

Figure 1, is a longitudinal central section of my improved pen and pencil mechanism.

Figure 2, is a like section of a portion of the same, showing the operation of the self-filling mechanism.

Figure 3, is a like section showing the pencil mechanism removed from the pen stock.

Figure 4, is a transverse section on the line 4-4 in Fig. 1.

In these drawings A indicates the hollow cylindrical barrel of a fountain-pen showing

the usual nib-holder A' secured in the lower end thereof in the usual manner.

Adjacent to the upper end of the barrel A is a transverse wall A² which is preferably integral with the circumferential wall of the barrel A; but if preferred may be secured therein in any other manner. This wall A² is provided with a central opening a therethrough. The upper end of the barrel A is provided with internal screw threads a' and I preferably place within this upper end of the barrel A, a suitable packing-gland a².

Engaging the screw threads a' in the upper end of the barrel A is a socket member B which thereby becomes an extension of the barrel A. Within the base of the socket member B is permanently and non-rotatably secured a tube B' which tube extends into the barrel A through the packing-gland a² and opening a in the partition wall A².

The tube B' is preferably provided with a longitudinal opening of square cross-section. Upon the tube B' and within the barrel A is placed a piston C which snugly fits the internal wall of the barrel A; said piston C being both slidable and rotatable upon the tube B'.

The piston C is provided with an L-shaped slot c which is adapted to receive a transverse pin b in the tube B' so that when the socket member B is unscrewed from the end of the barrel A and drawn backwardly therefrom, the tube B' can be rotated until the transverse pin b enters into the slot c on the piston C; and when the transverse pin b is engaged in said slot the piston C can be moved longitudinally in the barrel A by means of the tube B'.

The outer end of the socket member B is provided with internal screw threads b' to receive a screw threaded nut B² which has a central cylindrical opening b² therethrough. Within the cylindrical opening b² is rotatably mounted a conical pencil point D which is provided with a longitudinal screw threaded opening D' in which a lead-holder d is placed, which is provided with a nut d' adapted to engage the internal threads in said pencil point D. This nut d' is provided with a stem d² preferably of square cross-section adapted to fit and slide in the longitudinal opening of the tube B', but which will not rotate therein.

The pencil point D is also provided with a screw threaded nipple d³ upon which a

ring-nut E is placed adapted to retain the point D in the nut B² and allow relative rotation of the pencil point D in the nut B². The pencil lead F is secured in the lead-holder d and extends therefrom through a suitable opening in the point D, and when it is desired to move the lead F longitudinally in the point D, the point D is rotated, which causes the nut d', which intermeshes 10 with the internal threads in the longitudinal opening D' to travel longitudinally in said opening thereby giving the desired movement to the lead F.

When it is desired to clean the pen the 15 socket B is unscrewed from the barrel A and withdrawn backwardly therefrom until the transverse pin b is properly engaged in the L-shaped slot c in the piston C, when, by means of the longitudinal movement of the 20 piston C in the barrel A water can be drawn inwardly and ejected from the barrel A. Likewise the barrel A can be filled with ink.

Having thus fully described the construction and operation of this invention, I do 25 not desire to limit myself to the exact mechanism shown and described, as many modifications can be made therein without departing from the scope of my invention;

therefore, what I claim as new and desire to secure by Letters-Patent is:—

30

1. In a writing instrument a hollow handle adapted to contain writing fluid, and having an internally threaded socket in the end thereof, a tube centrally secured into said hollow handle, a lead pencil feeding mechanism comprising a lead-holder and feeding screw adapted to be screwed into said socket, and a stem on said feeding screw adapted to non-rotatably telescope in said tube.

35

2. In a writing instrument, a hollow-handle having a socket in the end thereof, a tube secured centrally in the bottom of said socket and extending therefrom into said hollow handle, a nut adapted to be non-rotatably secured in said socket, a tapered end member having an internally threaded bore in said member rotatably mounted in said nut, a rearwardly extending shank on said tapered end member, a collar screwed on 40 said shank back of said nut, a lead-holder engaging said internally threaded bore, and a stem on said lead-holder slidably and non-rotatably extending into said tube.

45

In testimony whereof I affix my signature.
FREDERICK WALDORF.
